UNITED STATES PATENT OFFICE.

JOHN H. McCUALEY, OF WICHITA FALLS, TEXAS, ASSIGNOR OF ONE-HALF
TO JAMES LOWENSTEIN, OF SAME PLACE.

PLACKET-FASTENER.

SPECIFICATION forming part of Letters Patent No. 599,672, dated February 22, 1898.

Application filed December 30, 1896. Serial No. 617,491. (No model.)

To all whom it may concern:

Be it known that I, JOHN H. McCUALEY, a citizen of the United States, residing at Wichita Falls, in the county of Wichita and 5 State of Texas, have invented certain new and useful Improvements in Placket-Holders; and I do hereby declare the following to be a full, clear, and exact description of the invention, such as will enable others skilled in the art to 10 which it appertains to make and use the same.

The object of this invention is to keep the placket closed under all ordinary conditions, to allow the dress to be drawn to either side without undue strain upon the skirt-band, to 15 keep the skirt-band at all times wholly concealed, to prevent sagging of the band at the point where its ends meet, and to secure all these advantages by a device that will not seriously wear the fabric by which it is 20 concealed.

In the accompanying drawings, Figure 1 shows the device in placket-closing position, only a small portion of the skirt and of the belt being shown. Fig. 2 shows the upper 25 part of the device with the members in the positions they occupy when the placket is partly opened. Figs. 3 and 4 are sections upon the lines 3 3 and 4 4 of Fig. 1.

In the figures, A is a skirt, and A' its band. 30 B is a belt, which may be a part of an upper garment or may be the common independent belt of leather or other material.

The body of the placket-holder consists of two thin flat strips C C', adapted to resist 35 edgewise strain, provided with perforations permitting the convenient attachment of the dress fabric and pivoted at their lower ends to the branches of a U-shaped clip D, respectively. Above the strips are horizontal bars

40 E E', provided upon their inner faces, respectively, with a hook F and an eye G to be engaged by said hook. These bars are also perforated, so that they may be readily sewed to the end portions of the band, respectively, 45 and are each provided with a downwardly-extending arm G', whose lower end is pivoted at H to the upper end of the corresponding strip C or C', of which the arm then forms a continuation. The pivotal points are pref-

50 erably below both the skirt-band and the belt B, and the axial lines of the pivots are preferably coincident in direction and parts of the same line. Each bar is also provided with an upwardly-extending arm I, adapted

to engage the belt B or some suitable device 55 borne thereby and at such point that the belt must always cover the band of the skirt. As shown, each arm I is bent to form a hook J to engage an eye K upon the inner face of the belt; but this construction merely illustrates one of many obvious internal and external connections.

By providing for connecting the bars to the belt the common somewhat V-shaped depression of the band's upper edge at this point is 65 wholly prevented and the appearance of ineffectual attempts to accomplish certain results by crude devices is eliminated. By pivoting the arms G' to the strips just below the belt the skirt is allowed to swing freely to 70 toward either side without either distorting the band and belt or without disclosing the presence of the strips C C'. In using the U-shaped clip at the lower ends of the clips they are allowed to swing as if upon a single pivot, yet 75 they are held apart so that there is room for inclosing them with the fabric without placing the latter in position to be subjected to undesirable strain in opening the placket or to be quickly worn by rubbing together adjacent 80 surfaces.

All parts of the device except the pivots may be made of thin spring-steel, and when 85 of this material the weight and cost are both slight.

What I claim is—

1. The combination with the strips pivotally connected at their lower ends, of the band-bars provided with the downwardly-extending arms pivoted to the upper ends of the 90 strips, respectively, and further provided with the upwardly-extending arms bearing devices to engage a belt or the like.

2. The combination with the strips pivotally connected at their lower ends by a U- 95 shaped clip, of the mutually engaging band-bars provided with the downwardly-extending arms pivoted to said strips, respectively, and having at their free ends the upwardly-extending hooked arms for engaging a belt 100 at points upon the opposite sides of the line of the strips.

In testimony whereof I affix my signature in presence of two witnesses.

JOHN H. McCUALEY.
